UNITED STATES PATENT OFFICE.

A. M. HILL, OF PHILADELPHIA, PENNSYLVANIA, ASSIGNOR TO CHARLES A. MILLER, OF SAME PLACE.

IMPROVEMENT IN LOCKS.

Specification forming part of Letters Patent No. 38,080, dated March 31, 1863.

To all whom it may concern:

Be it known that I, A. M. HILL, of Philadelphia, Pennsylvania, have invented an Improvement in Locks; and I do hereby declare the following to be a full, clear, and exact description of the same, reference being had to the accompanying drawings, and to the letters of reference marked thereon.

My invention relates to that class of locks and keepers for the same, which are used in connection with ordinary doors; and my improvement consists in a latch hung to a lock, connected to springs or their equivalents, and arranged in respect to the hub substantially as described hereinafter, so that a horizontal as well as vertical movement may be imparted to the outer end of the latch, the whole being combined with a keeper having two inclined planes.

The object of my invention has been to produce a cheap and simple lock which can be placed on a right or left handed door without any change as regards the interior parts of the lock.

In order to enable others skilled in the art to make and use my invention, I will now proceed to describe its construction and operation.

On reference to the accompanying drawings, which form a part of this specification, Figure 1 is a front view of a rim-lock and keeper with a portion of one plate of the lock removed in order to show the latch-bolt; Fig. 2, the same with the latch-bolt in a position differing from that seen in Fig. 1; Fig. 3, a vertical section of the keeper on the line 1 2, Fig. 2.

Similar letters refer to similar parts throughout the several views.

The box or casing A of the lock has its opposite sides formed alike, so that it may be secured either to a right or left handed door.

A hub, B, having two arms, *a a*, is arranged to turn as usual in the opposite sides of the lock, and has a square opening for receiving the square spindle which is furnished with the usual handles or knobs.

D is the latch-bolt, one end of which is forked, so as to embrace and be guided by the hub B, each arm *e* of this forked end of the latch-bolt having a projection *d*, against which bears one of the arms *a* of the hub B.

The outer end, *h*, of the latch-bolt is arranged to pass through an opening, *x*, in the

front edge of the lock, this opening being of sufficient height to allow for the depression of the end *h* of the latch-bolt to the extent described hereinafter.

Two coiled springs, H and H', serve to connect the latch-bolt to a projection, *m*, on the case of the lock. These spring are arranged, the spring H to move the latch-bolt outward when the handles or knobs are released, and the spring H' to raise the outer end, *h*, of the bolt.

G is the keeper, midway between the top and bottom of which is an opening, *m*, this opening being bounded above by the termination of the inclined plane *n* and below by the termination of a similar inclined plane *n'*, both planes being formed by ribs projecting above the surface of the keeper, and both planes inclining from these ribs downward to the opening *m*. This opening *m* of the keeper and the opening *x* of the lock bear toward each other the relative position shown in Figs. 1 and 2, the end *h* of the latch-bolt projecting beyond the edge of the lock, and behind the inclined plane *n* of the keeper when the release of the handles or knobs permits the spring H to move the latch-bolt forward.

By turning the hub B one or other of its arms, *a*, will bear against one or other of the projections, *d*, and withdraw the bolt so that its end *h* will be moved into the opening *x* from behind the inclined plane *n* of the keeper G, the latch-bolt during this movement being guided at one end by the upper edge of the opening *x*, against which it is pressed by the spring H', and at the opposite end by the hub B.

When an open door provided with the above-described lock has to be closed by simply pushing the door, the side of the projecting end *h* of the latch-bolt will strike the inclined plane *n*, and will necessarily be depressed, as seen in Fig. 2, until the end *h* is brought opposite to the opening *m*, between the two inclined planes of the keeper, when the spring H will at once elevate the latch-bolt until it strikes the upper edge of the opening *x*, the end *h* of the bolt taking its place behind the inclined plane *n* of the keeper.

It will now be seen that the latch-bolt D is arranged to have both a horizontal reciprocating motion and a vibrating motion, and that

the hub serves to guide one end of the bolt during its horizontal movement and serves as a center on which to turn when it vibrates.

As shown in the drawings, the lock is secured to a door which opens from left to right, but as both sides of the lock are finished alike, it can without any change of the interior devices be secured to a door opening from right to left, in which case the keeper must be reversed, the lower inclined plane, n' , being uppermost, so as to be acted upon by the end h of the bolt.

I am aware that a keeper having a double-inclined rib or flange has been heretofore used in connection with the latch-bolt of a lock. I therefore do not claim, broadly, such a device; but

I claim as my invention and desire to secure by Letters Patent—

The latch D, hung to the lock, connected to the springs H and H', or their equivalents, and arranged in respect to the hub B, substantially as described, so that a horizontal as well as vertical movement may be imparted to the outer end of the said latch, the whole being combined with a keeper having two inclined planes.

In testimony whereof I have signed my name to this specification in the presence of two subscribing witnesses.

A. M. HILL.
